Primary Examiner — Jack Reickel*Assistant Examiner* — Salamah Jordan(57) **CLAIM**

The ornamental design for a trampoline, as shown and described.

DESCRIPTION

FIG. 1 is a top perspective view of the trampoline;

FIG. 2 is a bottom perspective view of FIG. 1;

FIG. 3 is a right view of FIG. 1;

FIG. 4 is a left view of FIG. 1;

FIG. 5 is a rear view of FIG. 1;

FIG. 6 is a front view of FIG. 1;

FIG. 7 is a top view of FIG. 1; and,

FIG. 8 is a bottom view of FIG. 1.

The broken lines shown on the drawings depict portions of the trampoline that form no part of the claimed design.

1 Claim, 8 Drawing Sheets(56)
